CLAIM

The ornamental design for a combined beam splitter and optical coupler for connecting a light source to a television camera during surgical procedures, substantially as shown and described.

DESCRIPTION

FIG. 1 is a perspective view of a combined beam splitter and optical coupler for connecting a light source to a television camera during surgical procedures showing our new design;

FIG. 2 is a front elevational view thereof;

FIG. 3 is a rear elevational view thereof;

FIG. 4 is a left side view.

FIG. 5 is a right side elevational view thereof;

FIG. 6 is a top plan view thereof;

FIG. 7 is a bottom view.

FIG. 8 is a perspective plan view showing the apparatus as employed with associated components.

FIG. 1

FIG. 2

FIG. 3

FIG. 4

FIG. 5

FIG. 6

FIG. 7

FIG. 8
